(57) **CLAIM**

What is claimed is the ornamental design for a frame, as shown and described.

DESCRIPTION

FIG. 1 is a perspective view of a frame, showing a first embodiment of the new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof, the bottom plan view being a mirror image thereof;

FIG. 6 is a perspective view of a second embodiment thereof;

FIG. 7 is a front elevational view of FIG. 6;

FIG. 8 is a rear elevational view of FIG. 6; and,

FIG. 9 is a left-side elevational view of FIG. 6, the right-side elevational view, top plan view, and bottom plan view all being a mirror image thereof.

The broken lines showing a photograph in FIGS. 1 and 6 and an aperture in FIGS. 1-3 and 6-8 are included for the purpose of illustrating the invention in use, and form no part of the claimed design.
